LOOM-STOPPING MECHANISM.

Application filed May 22, 1926. Serial No. 110,885.

This invention relates to looms and is more particularly directed to loom stopping mechanism whereby the loom is stopped on the occurrence of a fault in the threads during weaving.

It is now the common practice to provide looms with stopping mechanisms to effect loom stoppage on the occurrence of a fault either in the warp threads or in the weft threads during weaving, so that the weaver may remedy the thread fault and continue to weave perfect cloth. It happens at times that the weaver maintains his hold on the shipper which controls the loom starting and stopping mechanism, and should a warp or weft fault occur at such times the loom will continue to run, with the result that imperfect cloth may be woven. For the production of perfect cloth it is essential that the loom be stopped on the occurrence of a fault or breakage in the threads during weaving and that the weaver at once remedy the fault.

One of the objects of the present invention is to provide loom stopping mechanism including a shipper, which, on the occurrence of a fault in the threads during weaving, will effect loom stoppage, even though the weaver may have hold of the shipper handle. In accordance with the present invention, the loom stopping mechanism includes a shipper which has a handle or hand piece movably mounted upon the shipper but is normally locked to the shipper, to enable the weaver to stop the loom by hand at his option, and means are provided for tripping the lock to free the shipper from the shipper handle control and insure loom stoppage on the occurrence of a thread fault, even though the weaver may hold the shipper handle in loom running position.

In the present embodiment of the invention, as shown, both warp and weft stop mechanisms are included, and connected to the shipper to effect loom stoppage on the occurrence of either a warp or weft fault, even though the shipper handle be held in loom running position, but the invention may obviously be employed in connection with either a warp stop mechanism or a weft stop mechanism or both.

The invention and new combination of

parts will best be made clear from the following description and the accompanying drawings of one good form thereof.

55

In the drawings:

Fig. 1 is a side elevation of a loom provided with the present invention, showing both a warp stop mechanism and a weft stop mechanism, some of the parts being broken away, and the loom being illustrated in running condition;

Fig. 2 is an enlarged side elevation showing the relation of parts when a weft fault has occurred and the loom is thereby stopped, notwithstanding the weaver holds the shipper handle in loom running position;

Fig. 3 is an enlarged perspective detail showing one form of lock and trip for controlling the connection between the shipper and shipper handle;

Fig. 4 is an edge view, parts being shown in section; and

Fig. 5 is a section on the line 5—5 of Fig. 4.

In accordance with the present invention, any usual form of warp stop mechanism or any usual form of weft stop mechanism may be employed, either or both, but in the present illustration of the invention the loom is provided with both a warp stop mechanism and a weft stop mechanism.

The loom frame 1 may be of usual construction having the lay 2 which is given its frontward and rearward movements through a pitman 3 connected to the crank shaft 4, and mounted at the rear of the loom is the warp beam 5 from which the warp threads *a* are withdrawn during weaving operation.

The warp stop mechanism, as hereinbefore noted, may be of any usual type but as illustrated it comprises the drop wires 6 which are normally held raised by the intact warp threads, and below the drop wires is the detector 7 supported on the rock shaft 8 for oscillatory movement below the drop wires. The rock shaft 8 has the arm 9 to which is connected a rod 10 which extends to the lower portion of the loom and is there connected at 11 to a cam follower 12 pivotally mounted at 13 and normally bearing upon a cam 14 on the lower or cam

shaft 15 under the influence of a spring 16', the construction being such that the detector 7 is given the usual oscillatory movement during loom operation. These parts may be as usual.

Secured to and extending from the rock shaft 8 is a dog actuating arm 16 to which is connected a rod 17 jointed at 18 to the tail piece 19 of a dog 20 pivotally mounted at 21 on the link 22 which is itself pivotally connected to the loom frame at 23. The construction is such that upon oscillatory movement of the detector, the dog 20 will be moved into inoperative position relative to a bunter 24 carried by the lay 2 and such movements may continue as long as the warp threads remain intact or without fault. Should a warp thread break or become too slack, however, the detector 7 will be arrested by the fallen drop wire and position the dog in the path of the bunter, thereby effecting loom stoppage through a train of mechanism presently to be described.

In the present instance of the invention, the lay 2 carries a center weft fork 25 pivotally mounted at 26 and connected at 27 with a downwardly extending rod 28 which controls the position of a knock-off finger 29 pivotally mounted at 30. The parts so far described may be as usual and the details thereof form no essential part of the present invention. The weft fork mechanism is such that should the finger 29 be lowered by the absence of weft in the shed, it will engage a projection 31 extending from the slide 32 which is mounted by pin and slot connection 33 to the loom frame or a bracket secured thereto.

Pivotally mounted upon the loom frame and preferably to the bracket which supports the slide 32 is the rocker arm 34 constituting a part of the loom stopping mechanism. The rocker 34 is pivotally mounted at 35 and its upwardly extending end 36 bears upon the front edge portion of the slide 32, the construction being such that should a weft thread fault occur the finger 29 will, on forward movement of the lay, move the slide 32 and effect rocking movement of the rocker 34.

Pivotally secured to the rocker 34 at 37 is the rod or connection 38 which also constitutes part of the loom stopping mechanism. The rod or connection 38 is provided with a slot 39 through which engages a pin or rod 40 secured to the shipper lever 41 which is itself pivotally mounted upon the loom frame at 42.

It has not been deemed necessary herein to show and describe the details of the stopping elements which extend to the clutch or belt mechanism which actuate the loom, since such details form no part of the present invention and are now well understood in the art.

The shipper 41 is provided with a handle or hand piece 43 which, as shown, Figs. 3 and 4, is pivotally connected to the shipper by the pin 44, the head 45 of which is enlarged to overlie the outer face of the shipper handle and such pin is shown as secured to the shipper 41 by a threaded bolt 46.

The shipper handle or hand piece 43 is therefore pivotally mounted upon the shipper and in order to connect the hand piece to the shipper, so that the latter may be moved by the weaver to stop the loom at his pleasure, the handle or hand piece 43 is connected to the shipper by a lock, the features of which are also associated with the warp and weft stopping mechanism as will later appear.

In the present instance of the invention, the shipper 41 is provided with a hollow boss 47 extended laterally therefrom, as indicated in Figs. 3 and 4, and mounted in the hollow boss 47 is the locking bolt 48 which passes through an opening 49 formed in the shipper 40 and is normally engaged in a recess or opening 50 formed in the hub portion of the handle or hand piece 43. The locking bolt 48 is normally under the influence of a spring 51 which may be conveniently mounted in the hollow boss 47 with its outer end resting against the face of an adjusting bolt 52, while its inner end rests upon the face 53 of the locking bolt 48, the normal tendency of the spring being to move the bolt into locking position to lock the handle or hand piece 43 to the shipper, and when the parts are so locked it will be obvious that the shipper may be moved by the loom attendant to stop the loom at will.

In accordance with the present invention, however, the handle or hand piece 43 is to be unlocked from the shipper on the occurrence of a fault in the threads during weaving, so that even though the loom attendant hold the shipper handle in loom running position, the loom will nevertheless stop by actuation of the stopping mechanism due to either a warp or weft fault.

Connected to the swinging link 22, which carries the dog 20, is a rod 54 which passes through the lug 55 extending from the stopping connector 38 and its front end portion is pivotally connected at 56 to a lock trip actuating mechanism, as will presently be explained. Interposed between the projection 55 and a shoulder 57 on the rod 54 is a spring 58 normally tending to move the rod 50 forwardly.

The rocker 34 has pivotally connected to it at 59, Fig. 1, an arm 60 which, like the rod 54, is connected at 56 to the lock trip actuating mechanism, the construction being such that upon the occurrence of either a warp or a weft fault in the construction shown, the rod 54 or arm 60 will be moved rearwardly and this rearward movement is

utilized in the present invention to actuate the lock tripping mechanism.

In the present instance of the invention, the lock tripping mechanism is constituted as a toggle, the lower arm 61 of which is pivotally mounted at 42 and its upper end is pivotally connected at 56 to the upper toggle 62 which is connected by a pin 63 to the shipper, said pin passing through a slot 64 formed in the upper toggle member. From the construction thus far described it will be apparent that upon rearward movement of the rod 54 or arm 60, the toggle will be straightened.

The upper member 62 of the toggle has an offset portion 65, best shown in Figs. 3 and 4, on which is pivotally mounted at 66 a trip 67. The trip 67 has its lower arm 68 connected to a spring 69 which normally maintains the trip in the position indicated in Fig. 4, with the lower arm 68 in contact with a stop 70.

Extending laterally from the locking pin 48 is an arm 71 which projects through an opening 72 formed in the boss 47, as indicated in Fig. 3, and one face of the arm 71 is rounded as at 73 so that upon upward movement of the trip 67 when the toggle is straightened, as hereinbefore described, the trip 67 will engage the rounded surface 73 and withdraw the locking bolt 48 from its locking position and thereby free the shipper handle 43 for movement relative to the shipper.

In the present instance of the invention, the trip 67 is formed as a by-pass, so that when the trip rises as described and withdraws the locking bolt from engagement with the shipper handle 43, the trip will rise beyond the projection 71 and on downward movement of the trip it may by-pass or yield when it comes into contact with the opposed face of the projection 71. This construction has proved to be a good practical form of locking trip, but the invention is not restricted thereto, as any form of trip which may serve to disconnect the shipper handle from the shipper on the occurrence of a warp or weft fault is within the purport of the present invention.

From the construction described it will be obvious that on the occurrence of either a warp or a weft fault, the stopping mechanism constituted by the rocker 34 and the connection 38 of the shipper, will be moved rearwardly to effect loom stoppage, and as either of said mechanisms are thus moved to stop the loom, the toggles 61 and 62 will be straightened by the connections 54 and 60 with the stopping mechanism to thereby actuate the trip and withdraw the locking bolt from locking engagement with the shipper handle, so that should the weaver have hold of the shipper handle when either the warp or weft stop mechanisms are called

into action by a fault in the threads, the shipper handle will be unlocked from the shipper to thereby prevent the shipper being held in loom running position by the weaver and thus loom stoppage will occur even though the weaver on the occurrence of a warp or a weft fault may hold the shipper handle in loom running position.

What is claimed is:

1. In a loom, the combination of loom stopping mechanism to effect loom stoppage on the occurrence of a fault in the threads during weaving, including a shipper, a hand piece normally locked to the shipper, and means actuated by the stopping mechanism to unlock the hand piece from the shipper to insure loom stoppage even though the weaver holds the hand piece in loom running position.

2. In a loom, the combination of loom stopping mechanism to effect loom stoppage on the occurrence of a fault in the threads during weaving including a shipper, a hand piece pivotally connected to the shipper, a lock normally locking the hand piece to the shipper, and a trip actuated by the stopping mechanism to trip the lock and free the shipper from the hand piece to effect loom stoppage even though the hand piece is held in loom running position.

3. In a loom, the combination of loom stopping means to effect loom stoppage on the occurrence of a fault in the warp or weft threads during weaving including a shipper, a hand piece connected to the shipper for relative movement therewith, a lock normally locking the hand piece to the shipper for conjoint movement therewith, and a trip for unlocking the hand piece from the shipper on the occurrence of a warp or weft fault to insure loom stoppage even though the hand piece is held in loom running position.

4. In a loom, the combination of warp and weft stopping mechanism including a shipper, a hand piece mounted on the shipper for movement relative thereto, a lock normally locking the hand piece to the shipper for movement therewith, and a trip connected to the warp and weft stopping mechanism to trip the lock and free the shipper from the hand piece when either the warp or weft stopping mechanism is actuated by the occurrence of a warp or weft fault to stop the loom.

5. In a loom, the combination of stopping mechanism to effect loom stoppage on the occurrence of a fault in the threads during weaving including a shipper, a hand piece connected to the shipper for movement relative thereto, a lock normally locking the hand piece to the shipper that the shipper may be moved to stopping position by the hand piece, and a trip actuated by the stopping mechanism to unlock the hand piece

from the shipper to insure loom stoppage even though the hand piece is held in loom running position.

6. In a loom, the combination of stopping mechanism to effect loom stoppage on the occurrence of a fault in the threads during weaving including a shipper, a hand piece connected to the shipper for movement relative thereto, a lock normally locking the hand piece to the shipper that the shipper may be moved to stopping position by the hand piece, and a trip connected to the shipper and actuated by the stopping mechanism to unlock the hand piece from the shipper to insure loom stoppage even though the hand piece is held in loom running position.

7. In a loom, the combination of loom stopping mechanism including a shipper, means connected thereto to effect loom stoppage on the occurrence of a fault in the warp or weft threads during weaving, a hand piece pivotally mounted on the shipper, a lock carried by the shipper and normally locking the hand piece from pivotal movement relative to the shipper that the shipper may be moved by the hand piece to stop the loom, and a trip connected to the warp and weft stopping means to free the hand piece from the shipper and insure loom

stoppage should the hand piece be held in loom running position.

8. In a loom, the combination of warp stop mechanism and weft stop mechanism, a shipper connected thereto to effect loom stoppage on the occurrence of either a warp or weft fault, a handle mounted on the shipper for movement relative thereto, a lock normally locking the handle from such relative movement that the shipper may be actuated by the handle to stop the loom, and a trip connected to and actuated by the warp and weft stopping mechanism to unlock the handle from the shipper to insure loom stoppage should the handle be held in loom running position.

9. In a loom, the combination of a shipper to start and stop the loom, a handle movably mounted on the shipper, a lock normally locking the handle from movement on the shipper, a trip for the lock, warp and weft stopping mechanisms, and connections between the lock trip and said mechanisms to free the shipper from control of the handle to insure loom stoppage even though the handle be held in loom running position on the occurrence of a fault in the threads.

In testimony whereof, I have signed my name to this specification.

MELVIN L. STONE.
